GEAR PUMP OR MOTOR

Yasuo Kita, Kyoto, Japan, assignor to Shimadzu Seisakusho Ltd., Kyoto, Japan

Filed June 2, 1965, Ser. No. 460,760

Claims priority, application Japan, July 31, 1964, (utility model), 39/61,017 (utility model), 39/61,018 (utility model), 39/61,019, 39/43,750

7 Claims. (Cl. 103—126)

This invention relates to gear pumps or motors, and more particularly to an improved construction for sealing gear peripheries.

Gear pumps or motors are conventionally made with an intermediate section including intersecting arcuate chambers to accommodate the gears, and end closures secured to the ends of the intermediate section to form the chamber ends. The intermediate section is formed either as a separate member from each of the end closures or as an integral part with one end closure. In any case, the gear chamber is subjected to a pressure gradient which varies from inlet pressure in the area adjacent the pump inlet to discharge pressure in the area adjacent the discharge side of the pump. Therefore, the portion of the gear peripheries near the pump inlet is subjected to less pressure tendency than the portions of the gear peripheries near the pump outlet. This unbalanced condition tends to urge the gears to the gear chamber wall at the inlet side of the pump and results in torque loss due to friction of tooth top of the gears. The torque loss increases the power required to turn the pump. In case of gear motors, it decreases the output.

In conventional gear pumps or motors, problems are also encountered due to dimensional interference between cooperating members and parts constituting the pump or motor assemblies. Highly accurate location and fine machining of the members are required to avoid dimensional interference therebetween. For example, the gear shafts must be exactly located in the respective required positions within the gear casing considering the pitch circles of the gears. The gear casing wall for covering the gear peripheries in sealing relationship must be finely machined so as to accommodate the addendum circles of the gears only keeping running clearance. Otherwise, interference will occur between the cooperating members and this results in deformation or abrasion. Even if such exact location and fine machining are once obtained, reproduction of them at reassembling cannot be expected, especially reproduction of complete sealing of the gear peripheries as originally obtained will be impossible.

Accordingly it is a primary object of the invention to resolve the above problems and to provide a new and improved gear pump or motor which can be operated at a high speed and under a high pressure.

Another object of the invention is to provide a gear pump or motor in which means for sealing the gear peripheries is separately formed from the casing whereby the sealing surfaces for the gear peripheries can be finely machined and reproduced without difficulties to accommodate the gear peripheral portions to be covered for pumping action.

Still another object is to provide a gear pump or motor in which the casing may be shaped in a form easy to manufacture such as a cylindrical form.

A further object is to provide a gear pump or motor in which means for sealing the gear peripheries can be replaced and located exactly in the required position within the casing.

A still further object is to provide a gear pump in which the outer limits of the gear teeth are prevented from coming no closer to the sealing surfaces, or sur-

faces with which they cooperate for the production of pump pressure, of the pump under the action of pump pressure and upon achievement of maximum intended pump pressure than to at least a relatively light contact with said sealing surfaces.

Yet another object of the invention is to provide improved means for balancing axial thrust of the thrust plates inserted between the end faces of the meshing gears and each of the end walls of the casing through the utilization of the fluid pressure within the casing.

Still another object is to provide a pump having an improved arrangement for filling the tooth spaces at the inlet side of the pump to enable complete filling of the tooth spaces at higher pump speeds than can be achieved when the fluid is fed into the gear teeth in a direction normal to the teeth.

A still further object is to provide a gear pump having an improved arrangement for relieving the fluid trapped in the tooth spaces as the gear teeth move into meshing engagement, and for filling the tooth spaces at the inlet side of the pump as the gear teeth move out of meshing engagement.

A further object of the invention is to provide a gear pump or motor in which the unit located within the casing is automatically maintained, without compulsory positioning, in position during operation.

The gear pump or motor according to the invention comprises a casing containing a pair of meshing pump gears therein, gear end sealing means on the opposite sides of the meshing gears and gear periphery sealing means and characterized in that said gear periphery sealing means is separately formed from said casing and only covers the portions of the gear peripheries near the meshing area substantially along the addendum circles of said gears.

In a preferred embodiment of the invention, the casing consists of a cylindrical wall body and end closures thereof. A pair of intermeshing gears are located within said casing in such a manner that the peripheries of the gears are spaced from the inner wall of the cylindrical body of the casing. For gear end face sealing, a pair of thrust plates are located on the opposite sides of the meshing gears. Gear periphery sealing means may comprise a member having arcually concave sealing surfaces corresponding to the addendum circles of the gears. Each of the thrust plates has peripheral portions for receiving the gear periphery sealing member so that the gear periphery sealing member may be supported by bridging it between the two thrust plates. The peripheral portions are so shaped as to receive the sealing surfaces of the sealing member in sealing engagement. The sealing member may be urged by spring means toward the thrust plates for sealing engagement therewith.

The cylindrical body of the casing may be secured to end closures by clamping it between the two enclosures by a plurality of at least three, and preferably four, bolts extending to the other end closure. The cylindrical body may be fixed in a definite position by inscribing these bolts with the inside wall of the cylindrical body.

Each of the thrust plates has at their opposite ends depressed areas spaced from the end walls of the end closures and from the end faces of the gears to receive the fluid pressure thereof in such a manner that each of the thrust plates is balanced in the axial direction.

The thrust plates and gear sealing member may coact to form substantially axially directed inlet and outlet passages for the fluid to be introduced into the tooth spaces at the inlet side and to be discharged from the tooth spaces at the outlet side.

Each of the two shafts for the two gears may be supported at its opposite ends through bearings by bores recessed in the end closures of the casing.

Each of the thrust plates has a pair of bores which cooperate with the bores in the end closures to support two gear shafts.

The driven shaft may be supported only by the thrust plates. In this case, the swing movement about the drive shaft of the unit including the driven shaft, the driven gear and the thrust plates may be prevented by inscribing the gear periphery sealing member with the inside wall of the cylindrical body of the casing.

Other objects and advantages of the present invention will be apparent from the following detailed description taken in conjunction with the drawings wherein:

FIGURE 1 is a central vertical longitudinal sectional view, as indicated by the lines 1—1 of FIGURES 3 and 4, of a typical form of the gear pump embodying the present invention;

FIGURE 2 is a vertical transverse sectional view taken along the line 2—2 of FIGURES 1 and 4;

FIGURE 3 is a vertical transverse sectional view taken along the line 3—3 of FIGURES 1 and 4;

FIGURE 4 is a horizontal sectional view taken along the lines 4—4 of FIGURES 2 and 3;

FIGURE 5 is an enlarged view of the portion indicated by the lines of 5—5 of FIGURE 1;

FIGURES 6a and 6b illustrate fluid pressure distribution at the opposite ends of the thrust plate shown in FIGURE 5;

FIGURE 7 is a central vertical longitudinal sectional view of the gear pump showing another embodiment of the invention;

FIGURE 8 is a vertical transverse sectional view taken along the line 8—8 of FIGURE 7 and

FIGURE 9 is a horizontal sectional view taken along the line 9—9 of FIGURE 8.

Referring now to the drawings, first particularly to FIGURES 1 to 5, the present invention is illustrated in connection with a gear pump, but it should be understood that the invention may be utilized in connection with a gear motor.

The pump includes a pair of intermeshing gears 21 and 22 mounted within a cylindrical casing 23. The casing 23 comprises a cylindrical side wall body 24 and end closures 25 and 26 of the opposite ends of the body 24. Hereinafter one end closure 25 is referred as the front head while the other end closure 26 is referred as the end cover plate. The cylindrical body 24 is clamped between the front head 25 and the end cover plate 26 by four bolts 27 which extend through the inside of the cylindrical body 24 from the cover plate 26 to the front head 25. The four bolts are arranged at the angular points of a rectangle and inscribed with the inside wall 28 of the cylindrical body 24 (best shown in FIGURES 2 and 3) so as to define and maintain the cylindrical body 24 in position. Though not shown in the drawings, it should be understood that the ends of bolts 27 terminate at the front head 25 and are screw-secured thereto.

The front head 25 is recessed to contain a ball-bearing 29 and a suitable oil-seal assembly 30. A drive shaft 31 extends through the ball bearing 29 and oil-seal assembly 30 and into the inside chamber 32 of the casing 23 to engage and drive the drive gear 21. The gear 21 is keyed to the shaft 31. The numeral 33 indicates the key which is fixed to the gear 21 and the numeral 34 indicates the key slot. The key slot 33 may be longer than the length of the key 32 and have an oil passage clearance 34a at its bottom. The drive shaft 31 is supported on the opposite sides of the gear 21 by a pair of needle bearings 36 and 37 which are in turn received at their outer ends within shallow bores 38 and 39 recessed in the front head 25 and the end cover plate 26, respectively. The driven gear 22 is mounted on a driven shaft 35 and keyed thereto. The driven shaft 35 is supported on the opposite sides of the gear 22 by a pair of needle bearings 40 and 41 which are in turn received at their outer ends within

shallow bores 42 and 43 recessed in the front head 25 and the end cover plate 26, respectively.

The intermeshed gears 21 and 22 are supported between a pair of thrust plates 44 and 45. The thrust plates 44 and 45 are at their inner ends in sliding contact and in sealing relationship with the end faces of the intermeshing gears 21 and 22 and abut at their outer ends the end wall 46 of the front head 25 and the end wall 47 of the end cover plate 26, respectively. The thrust plates have bearing bores 48, 49 and 50, 51 which cooperate with the bores 38, 42 and 39, 43 to receive the needle bearings 36, 40 and 37, 41, respectively. The inner ends 48a, 49a of the bores 48, 49 are in registry with the right ends of the bearings 36, 40 and the inner ends 50a, 51a of the bores 50, 51 are in registry with the left ends of the bearings 37, 41, respectively (FIGURE 1). The inner ends of the needle bearings 36 and 37 are spaced from end faces 90 of the gear 21. The annular space 91 between the inner end of the bearing 36 and the end face 90 of the gear 21 communicates through the needle bearing 36 and an oil passage 92 to a drain port 93. The annular space 91 also communicates through oil passage clearance 34a of the bottom of the key slot 34 to the annular space 94 between the inner end of the bearing 37 and the corresponding end face of the gear 21. The drain port 93, the oil passage 92 and the oil passage clearance 34a thus form means for lubricating the bearings 36 and 37. Similar lubricating means may be applied to the bearings 40 and 41. The needle bearings 36, 37, 40 and 41 are thus maintained in position and they in turn rotatably support the two shafts 31 and 35 in parallel and spaced relationship.

The inside wall 28 (see FIGURE 2) of the cylindrical body 24 is spaced from the peripheries of the gears 21 and 22. The peripheral portions of the gears 21 and 22 immediately before and behind the meshing area are covered by gear periphery sealing members 52 and 53. As it is assumed that the drive gear 21 rotates clockwise (FIGURES 2 and 3), the sealing member 52 covers the peripheral portions of the gears 21 and 22 immediately behind the meshing area while the sealing member 53 covers the peripheral portions of the gears 21 and 22 immediately before the meshing area. Each of the sealing members 52 and 53 has a pair of arcually concave surfaces 54 and 55 for covering the peripheral portion of the gear 21 and the periphery portion of the gear 22, respectively. These surfaces 54 and 55 are concentric with the gears 21 and 22 and correspond to their respective addendum circles with the running clearance. The junction edge 63 of the two surfaces 54 and 55 opposes the maximum meshing point of the gears 21 and 22. The gear peripheral sealing members 52 and 53 are elongated in directions parallel to the shafts 31 and 35 and bridge between the two thrust plates 44 and 45. Each of the thrust plates 44 and 45 has peripheral surfaces 56 and 57 corresponding to the two concave surfaces 54 and 55. The sealing members 52 and 53 are urged by suitable means, for example, leaf springs 58 and 59, toward the gears 21 and 22 and the thrust plates 44, 45 so that the periphery portions of the gears 21 and 22 immediately before and behind their meshing area may be sealed with running clearance and the concave surfaces 54 and 55 of the sealing members 52 and 53 may be received in sealing relationship by the peripheral surfaces 56 and 57 of the thrust plates 44 and 45.

The front head 25 has a fluid inlet passage 60 and a fluid outlet passage 61, best shown in FIGURE 4. The sealing member 52 is provided with an axial flow passage 62 behind the edge 63 of the junction of the two arcual surfaces 54 and 55. The axial flow passage 62 communicates at its one end with the inlet passage 60 of the front head 25. The sealing member 52 also has a pair of openings 64 and 65 on the line of the junction edge 63 at the opposite sides of the meshing gears 21 and 22. The axial flow passage 62 communicates through these

openings 64 and 65 with substantially axially directed inlet passage spaces 66 and 67 formed between the sealing member 52 and each of the thrust plates 44 and 45. The inlet passage space 66 also communicates directly with the inlet passage 60 of the front head 25. The inlet 60, the axial flow passage 62, the openings 64, 65 and the spaces 66 and 67 thus form inlet passage means for the fluid to be pumped.

Most of the inflow is axially introduced along the inlet passage spaces 66 and 67 into the tooth spaces at the inlet side, although some of the inflow may be introduced into the tooth spaces in directions normal to the teeth. The axially introduced inflow enables complete filling of the tooth spaces at the inlet side of the pump at higher pump speeds than can be achieved hitherto. It is because the flow resistance is far smaller in the axial direction than in the circumferential direction.

Outlet passage means similar to the above mentioned inlet passage means may be formed in the sealing member 53. The sealing member 53 is provided with an axial flow passage 68 behind the edge 63 of junction of the two concave surfaces 54 and 55. The axial flow passage 68 communicates at its one end with the outlet passage 61 of the front head 25. The sealing member 53 also has a pair of openings 70 and 71 on the line of the junction edge 63 and on the opposite sides of the meshing gears 21 and 22. The axial flow passage 68 communicates through these openings 70 and 71 with substantially axially directed outlet passage spaces 72 and 73 formed between the sealing member 53 and each of the thrust plates 44 and 45. The outlet passage space 72 also communicates directly with the outlet passage 61 of the front head 25. The spaces 72 and 73, the openings 70 and 71, the axial flow passage 68 and the outlet 61 thus form outlet passage means for the high pressure fluid. The axial flow of the discharge fluid along the spaces 72 and 73 enables the fluid trapped in the tooth spaces to be relieved so that entrapment of the fluid in the intertooth spaces may be prevented.

In connection with the above, it is preferred that closure by the sealing member 54 of the periphery of the intermeshing gears 21 and 22 at its inlet side (low pressure side) is made as close to the meshing point as possible. This may be obtained by extending the junction edge 63 toward the meshing point of the gears 21 and 22 as close thereto as possible. It is also preferred to reduce the size of the inlet openings especially, the junction opening of the inlet passage 60 and the space 64, so that the tooth spaces behind the meshing point may be as small as possible. These features are disclosed in my copending U.S. patent application Ser. No. 375,081 filed on June 15, 1964.

The two thrust plates 44 and 45 are of identical construction in a substantially spectacles-shaped form, arranged symmetrically with respect to the intermeshing gears 21 and 22. The end elevation at the front head side of the thrust plate 44 is illustrated in FIGURE 2 and the end elevation at the gear side of the thrust plate 45 is illustrated in FIGURE 3. As shown in FIGURE 2, the outer end of each of the thrust plates 44 and 45 has end surface areas 86 which are in contact with the end wall 46 of the front head 25 and depressed areas 87 which are spaced from the end wall 46 of the front head 25. The inner end of each of the thrust plates 44 and 45 has also a contact surface area 88 engaging the end surfaces 90 of the gears 21 and 22 and depressed areas 89 spaced from the end surfaces 90 of the gears 21 and 22, as shown in FIGURE 3. Suitable dimensioning of these non-contact surface areas 87 and 89 enables the thrust plates 44 and 45 to be automatically balanced in the axial direction whereby no axial thrust is applied to the intermeshing gears 21 and 22.

Now I consider the pressure distribution of the opposite ends of the thrust plate 44 in a vertical and radial direction. Referring to FIGURE 5, the depressed area 87 at

the outer end of the thrust plate 44 has a vertical and radial length a . As it is assumed that the fluid pressure in the chamber 32 within the casing 28 is P , the pressure acting on the outer end of the plate 44 is considered $(P) \times (a)$ since the fluid pressure P is applied to the whole length a . On the other hand it is supposed that the depressed area 89 and the contact area 88 at the inner end of the plate 44 have the vertical and radial lengths b and c , respectively. The fluid pressure P acts on the whole length b of the depressed area 89. If it may be assumed that the pressure at the space 91 between the inner end of the needle bearing 36 and the end face 90 of the gear 21 is zero, the pressure distribution of the contact surface 88 in the direction of the length c is considered as shown in FIGURE 6b since there would be a pressure gradient due to the existence of a fluid film between the sliding contact surfaces 88 and 90. The total pressure applied at the inner end of the plate 44 is, therefore, given as follows:

$$P \times b + \frac{P}{2} \times c = P \left(b + \frac{c}{2} \right)$$

Accordingly, if three factors a , b and c are selected to satisfy the formula

$$a = b + \frac{c}{2}$$

the axial thrust forces in the opposite directions at the opposite ends of the plate 44 is completely balanced and therefore, no axial thrust is applied to the gear 21. It will be appreciated that in order to prevent the gear 21 from receiving thrust from the thrust plate 44 the fluid pressure receiving surface area 87 at the outer end of the plate 44 must be at least smaller than the total areas of the non-contact surface 89 and the contact surface 88 at the inner end of the plate 44. In the embodiment illustrated in the drawings, this is achieved by forming bores 48 and 49 at the outer end of the plate 44 for receiving the needle bearings 36 and 40. The above mentioned means for balancing the thrust plate 44 may be applied to the other thrust plate 45 as well.

In order to seal around the junction opening 75 at which the inlet passage 60 communicates with the axial flow passage 62 and the passage space 66, an O-ring 76 is inserted between the end wall 46 of the front head 25 and the contact surfaces thereto, namely the ends of the sealing member 52 and the thrust plate 44, so as to surround the opening 75 as best shown in FIGURES 2 and 4. Similarly, in order to seal around the junction opening 79 at which the outlet passage 61 communicates with the axial fluid passage 68 and the passage space 72, an O-ring 80 is inserted between the inner wall 46 of the front head 25 and the contact surfaces thereto, namely, the ends of the covering member 53 and the thrust plate 44, so as to surround the opening 79. In this manner leakage of the pressure oil from the outlet side to the inlet side through the clearance which might be produced between the end wall 46 of the front head 25 and the contact end surface of the member 44 is prevented. Instead of two O-rings 76 and 80, any other seal means such as rubber packings or the like may be used. Symmetrically to the above mentioned two O-rings 76 and 80, there are inserted two O-rings 82 and 83 between the end wall 47 of the end cover plate 26 and the contact surfaces thereto, namely opposite end surfaces of the sealing members 52 and 53 and the outer end surfaces of the thrust plate 45, so that the unit comprising the meshing gears 21 and 22, a pair of thrust plates 44 and 45, and a pair of covering members 52 and 53 may be supported within the casing 23 in a completely balanced condition in the axial direction. It should be understood that, in addition to completely balancing the axial thrust of each of the thrust plates 44 and 45, suitable dimensioning of the depressed areas 87 and 89 of the thrust plates 44 and 45 may also be utilized for adjustment of the contact pressure of each

of the members 44 and 45 to the gears 21 and 22, which is very important for both sealing and sliding engagement therebetween.

The fluid inducted from the inlet passage 60 by the pump action of the gears 21 and 22 is discharged within the casing chamber 32, the boundaries of which are defined by the cylindrical body 24, the front head 25 and end cover plate 26. After completely filling the chamber 32, the fluid is discharged to the outlet passage 61. During pumping operation, the pressure in the chamber 32 of the casing 23 is higher than that of the inlet passage 60. This pressure difference serves to urge the covering member 52 toward the peripheries of the gears 21 and 22. Accordingly, it is not necessary to apply a large biased force to the member 52 by the spring means 58. The leaf spring 58 may be replaced by any other supporting means which merely restrict retirement of the member 52 from the engaging position. To the contrary, the pressure at the outlet passage 61 often becomes higher than that of the chamber 32. Accordingly it would be necessary to use a leaf spring 59 having a relatively strong elasticity sufficient to overcome the pressure difference therebetween.

In principle pumping action is sufficiently obtained with only one of the sealing members 52 and 53, dispensing with the other. For example, the sealing member 53 at the outlet side may be omitted from the assembly illustrated in the drawings. In this case, the outlet passage may be formed in the cylindrical body 24.

In the embodiment illustrated in FIGURES 1 to 4, the shafts 31 and 35 are supported through needle bearings 36, 37 and 40, 41 by the front head 25 and the end cover plate 26 at the bores 38, 39 and 42, 43 so that the thrust plates 44 and 45 scarcely suffer from any radial force from each shaft or torque about the drive shaft 31. If the bores 48, 49, 50 and 51 for receiving the needle bearings 36, 40, 37 and 41 are finely machined so as to exactly center on the respective shafts 31 and 35, interference which may result in abrasion will scarcely occur between the other parts in contact therewith.

FIGURES 7 to 9 illustrate another embodiment of the invention in which a modification is made for driven shaft supporting means. The same reference numerals as in FIGURES 1 to 5 indicate similar and corresponding members or portions. Only different features and effects from those described with reference to the embodiment illustrated in FIGURES 1 to 5 are described hereinbelow.

The gear periphery sealing members 52 and 53 have arcual peripheral surfaces 101 and 102 which are inscribed with the inside wall of the cylindrical body 24. No biasing means such as leaf springs 58 and 59 illustrated in FIGURES 2 to 4 is used with this embodiment. The bearings 40 and 41 receiving the driven shaft 35 are not supported in fixed positions, though the outer ends of them are inserted in the respective shallow bores 103 and 104, since the diameter of each of the bores 103 and 104 is larger than the external diameter of each of the bearings 40 and 41 as shown in FIGURE 7. The combination of driven gear 22, the driven shaft 35 and the needle bearings 40 and 41 is supported and hung by a pair of thrust plates 44 and 45 from the drive shaft 31. The thrust plates 44 and 45 and the sealing member 52 and 53 engaged in sealing relationship thereto are maintained in position by engagement of either one of sealing members 52 and 53 to the inside wall 28 of the body 24 under torque about the drive shaft 31 according to the direction of rotation of the shaft 31 during operation. The limit of the swing movement of the unit comprising the thrust plates 44 and 45, the driven shaft 35, the driven gear 22 and the sealing members 52 and 53 depends on the position of the drive shaft 31 and the shape of the peripheries 101 and 102 of the members 52 and 53. In comparison with the embodiment illustrated in FIGURES 1 to 5, the embodiment illustrated in FIGURES 7 to 9 is advantageous in that compulsory positioning of the various e-e-

ments may be avoided because they are automatically maintained in position during operation. The latter embodiment may dispense with either one of the sealing members 52 and 53 as well as in the former embodiment.

Although the above description has been made in connection with the gear pumps, it will be understood that any of the above embodiments may be used as a gear motor as it is without any special modification.

Particular attention is invited to the following features which greatly improve the pump or motor over prior structures:

(1) The sealing members 52 and 53 are formed separately from the casing 23. This facilitates finely machining the sealing surfaces 54 and 55 for ensuring the sealing of the gear peripheries at which pumping action is effected. The sealing members 52 and 53 can be replaced by new ones. Reproduction of the sealing surfaces 54 and 55 is also easy.

(2) The side wall 24 of the casing 23 may be shaped in a cylindrical form. This enables manufacturing the casing more expeditiously and less expensively. In addition, the cylindrical form of the casing is durable in construction and pressure distribution is uniform all over the inside wall 28 of the body. It is not necessary to finely machine the inside wall 28 of the cylindrical body 24.

(3) The cylindrical body 24 is clamped between end closures 25 and 26 by bolts 27 which extend through the inside of the cylindrical member from one end closure 26 to the other 25. The cylindrical body is provided with no bolt-securing holes. This may reduce the thickness of the cylindrical body 24 to a great extent.

(4) The cylindrical body 24 is maintained in position by four bolts 27 which are inscribed with the inside wall 28 of the body 24. No special means is required for positioning the cylindrical body 24.

(5) The sealing members 52 and 53 bridge between the thrust plates 44 and 45. This facilitates the support of sealing members 52 and 53 and both assembling and disassembling of the unit are easy.

(6) Suitable dimensioning of the fluid pressure receiving areas at the opposite ends of the thrust plates 44 and 45 makes it possible to balance axial thrust which might be applied to the intermeshing gears 21 and 22. Desirable contact pressure is also obtained between the thrust plates and the gear end faces for sealing engagement therebetween.

(7) Substantially axially directed inlet passage spaces 66 and 67 facilitate introduction of the fluid to be pumped into the tooth spaces. Cavitation may be avoided.

(8) Substantially axially directed outlet passage spaces 72 and 73 may prevent the entrapment of the fluid in the tooth spaces.

(9) The unit including the driven shaft 35, the driven gear 22, the thrust plates 44, 45 and the sealing members 52, 53 is allowed to swing about the drive shaft at the non-operating state, but during operation the swing movement of the unit is constrained by pressure engagement of either of the sealing members 52, 53 to the inside wall of the cylindrical body 24 of the casing 23. Compulsory rotation of the members constituting the unit can be avoided.

What is claimed is:

1. A gear pump or motor comprising, a casing having a side wall and opposed end closures, said casing having a fluid inlet and a fluid outlet in one of said end closures, a pair of intermeshing gears located within said casing, a gear periphery sealing member covering the peripheral portions of said gears near their meshing area at the low pressure side, said gear periphery sealing member having arcually concave sealing surfaces corresponding to the addendum circles of said gears and being floatingly supported within said casing so that during operation said sealing member is automatically urged by the pressure within said casing toward the peripheral surfaces of said meshing gears, and a pair of thrust plates located on oppo-

site sides of said intermeshing gears, each of said thrust plates having peripheral portions for receiving and positioning said gear periphery sealing member therebetween, said peripheral portions being shaped as to receive the sealing surfaces of said gear periphery sealing member in sealing relationship, said thrust plates and a gear end sealing member coacting to form inlet and outlet passages for the fluid to be introduced into tooth spaces at the inlet side and to be discharged from tooth spaces at the outlet side, said inlet and outlet passages being formed substantially in axial directions to and communicating with said respective fluid inlet and outlet.

2. A gear pump or motor as defined in claim 1, wherein said side wall is cylindrically shaped.

3. A gear pump or motor as defined in claim 1, wherein said gear periphery sealing member is urged by spring means toward said thrust plates for sealing engagement therewith and for covering said gear periphery portions in sealing relationship.

4. A gear pump or motor as defined in claim 1, wherein each of said thrust plates has at its opposite ends first recessed areas spaced from the end walls of said end closures and second recessed areas spaced from the end faces of said gears, said first and second recessed areas adapted to receive fluid pressure therein so that each of said thrust plates is balanced in the axial direction.

5. A gear pump or motor as defined in claim 4, wherein the first fluid pressure receiving surface area of each of said thrust plates is smaller than that of the second fluid pressure receiving surface area.

6. A gear pump or motor comprising, a casing having a side wall and opposed end closures, said casing having a fluid inlet and a fluid outlet in one of said end closures, a pair of intermeshing gears located within said casing, a pair of gear periphery sealing members covering the peripheral portions of said gears near their meshing area at the inlet side and at the outlet side, respectively, each of said gear periphery sealing members having arcually concave sealing surfaces corresponding to the addendum circles of said gears and being floatingly supported within said casing so that during operation the sealing member at the lower pressure side is automatically urged by the pressure within said casing toward the peripheral surfaces of said meshing gears, and a pair of thrust plates located on opposite sides of said intermeshing gears, each of said thrust plates having peripheral portions for receiving and positioning said gear periphery sealing members therebetween, said peripheral portions being shaped as to receive the sealing surfaces of said gear periphery sealing members in sealing relationship, said thrust plates and a gear end sealing member coacting to form inlet and outlet passages for the fluid to be introduced into tooth spaces at the inlet side and to be discharged from tooth spaces at the outlet side, said inlet and outlet passages being formed substantially in axial directions to and communicating with said respective fluid inlet and outlet,

7. A gear pump or motor comprising, a casing having a side wall and opposed end closures, a drive gear, a driven gear meshing with said drive gear, a drive shaft for mounting said drive gear thereon, said drive shaft being supported at its opposite ends through bearings in bores recessed in said end closures, a driven shaft for mounting said driven gear thereon, a pair of gear periphery sealing members covering the peripheral portions of said gears near their meshing area at the inlet side and at the outlet side, respectively, each of said gear periphery sealing members having arcually concave sealing surfaces corresponding to the addendum circles of said gears and being floatingly supported within said casing so that during operation the sealing member at the lower pressure side is automatically urged by the pressure within said casing to the peripheral surfaces of said meshing gears, and a pair of thrust plates located on opposite sides of said intermeshing gears, each of said thrust plates having peripheral portions for receiving and positioning said gear periphery sealing members therebetween, said peripheral portions being shaped as to receive the sealing surfaces of said gear periphery sealing members in sealing relationship, said thrust plates and a gear end sealing member coacting to form inlet and outlet passages for the fluid to be introduced into tooth spaces at the inlet side and to be discharged from tooth spaces at the outlet side, said inlet and outlet passages being formed substantially in axial directions to and communicating with said respective fluid inlet and outlet, said thrust plates supporting said driven shaft through bearings whereby the unit comprising said driven shaft, said driven gear, said thrust plates and said gear periphery sealing members is allowed to swing about said drive shaft at the non-operating state while during operation the swing movement of said unit is constrained by pressure engagement of one of said gear periphery sealing members against the inside wall of said side casing.
